Inventor,
John J. Harris by his Atty
W. Randolph Key

United States Patent Office.

JOHN J. HARRIS, OF ST. LOUIS, MISSOURI, ASSIGNOR TO HIMSELF.
RICHARD MORGAN, AND JOHN GAYSO.

Letters Patent No. 90,534, dated May 25, 1869.

IMPROVEMENT IN SAWING-MACHINES.

The Schedule referred to in these Letters Patent and making part of the same.

To all whom it may concern:

Be it known that I, JOHN J. HARRIS, of St. Louis, in the county of St. Louis, and State of Missouri, have made certain new and useful Improvements in Portable Wood-Sawing Machines; and I do hereby declare that the following is a full and clear description thereof, reference being had to the accompanying drawings, and to the letters of reference marked thereon.

The nature of this invention is in certain improvements in detail construction, hereinafter more specially described.

To enable those skilled in the art to make and use my improved machine, I will proceed to describe its construction and operation.

Figure 1, of the drawings, is a side elevation of the improved apparatus.

Figure 2 is a plan of the same.

The frame A has two handles, *a*, and a wheel, *a'*, similar, in many respects, to a wheelbarrow.

On the top of this frame A is erected another, A', which sustains the operative parts of the machine.

A driving-shaft, B, has its bearings in this frame A', and is operated by the hand-crank B', through the medium of the cog-gearing *b*.

The shaft B carries a driving-wheel, B², and a wrist, *b'*, attached to this wheel, operates the pitman or connecting-rod C, which rod communicates motion to the counter-shaft D.

The connecting-rod C has a slot, *c*, in its central part, which receives the stationary pin *c'*, fixed in the

frame A', and, in passing this pin, the connecting-rod is compelled to act with a leverage on the wheel D' of the counter-shaft D.

The belt *e* communicates motion, from the shaft D, to the saw-arbor E, on the outer end of which is placed a small circular saw, E'.

A small sliding carriage, F, has its ways in the top beams of the frame A', and is arranged to slide back and forth near the saw, so as to carry wood to it when pushed forward by the operator.

The requirements of a machine of this character are such, that both the operating-crank B' and the wood-table F should be elevated sufficiently to be within the easy reach of a man standing up; hence these important parts are elevated on top of the frame A', and the pitman C is employed to transfer the power from the driving-shaft to the other operative parts, as above described.

Having described my invention,

What I claim, is—

Connecting the two driving-wheels of a sawing-machine, by a slotted pitman, which acts upon and is guided by a shaft passing horizontally through it, all constructed and operating substantially as described.

In testimony whereof, I hereunto set my hand, in presence of—

JOHN J. HARRIS.
